CIGARETTE PACK DISPENSER

Maurene J. Ball, 6531 Monaco St.,
Commerce City, Colo. 80022

Filed Sept. 11, 1974, Ser. No. 504,879

Term of patent 14 years

Int. Cl. D6—04

U.S. Cl. D6—114

FIG. 1 is a front elevational view of the cigarette pack dispenser showing my new design;

FIG. 2 is a side elevational view, the opposite side being identical to the one shown;

FIG. 3 is a top plan view;

FIG. 4 is a bottom plan view.

I claim:

The ornamental design for a cigarette pack dispenser, substantially as shown and described.
